UNITED STATES PATENT OFFICE.

EDWARD MOORE, OF SYRACUSE, NEW YORK.

COMBUSTION-ENGINE.

1,098,824.

Specification of Letters Patent. Patented June 2, 1914.

Application filed September 8, 1908. Serial No. 452,075.

To all whom it may concern:

Be it known that I, EDWARD MOORE, of Syracuse, in the county of Onondaga, in the State of New York, have invented new and useful Improvements in Combustion-Engines, of which the following, taken in connection with the accompanying drawings, is a full, clear, and exact description.

This invention relates to certain improvements in combustion engines and refers more particularly to the two cycle reciprocating type in which the combustible fluid is compressed and ignited at the end of each compression stroke and the spent gases are discharged and fresh fuel supplied at the end of the out stroke of the piston. It is, therefore, necessary in this type of engine to admit the explosive charge and discharge the spent gases at each cycle of movement of the piston and although this intake and exhaust is almost instantaneous and practically simultaneous, it nevertheless requires an appreciable period of time to permit the cylinder to properly cleanse itself of the spent gases and to admit a proper amount of explosive fuel so that in practice, the power decreases as the speed of the engine increases particularly when the speed is such that the interval of time between the opening and closing of the ports by the piston will not allow the entrance of a proper amount of explosive fuel and cleansing of the cylinder from spent gases.

My main object, therefore, which is similar to that set forth in my Patent #948,336, of Feb. 8, 1910, is to provide the cylinder with intake and exhaust ports of ample size to assure the entrance of the fresh explosive mixture and exit of the spent gases during a minimum interval of time between the opening and reclosing of such ports under a maximum speed and at the same time to provide means whereby the effective lengths or leads of these ports may be varied from maximum to minimum at the will of the operator. In other words, I have sought to maintain a more uniform interval of time between the complete opening and closing of the ports by the piston under varying speeds of action so that such interval of time under high speed may be practically the same as under low speed for the purpose of maintaining the full power of the engine under all speeds.

Other objects and uses relating to specific

structural elements of the engine will be brought out in the following description.

In the drawings—Figures 1 and 2 are longitudinal vertical sectional views taken at right angles to each other of the cylinders and contiguous elements of an internal combustion engine showing the various features of my invention.

In order to demonstrate the practicality of my invention, I have shown a cylinder —1— as provided with an internal combustion chamber —2— and inlet and exhaust ports 3 and —4—, said cylinder being provided with a chamber —5— for the reception of a cooling medium forming a water jacket for the combustion chamber and is also provided with additional ports —7— and —8—, the port —7— communicating with an intake pipe —9— which may be connected to a carburetor or any source of fuel supply while the port —8— is connected by a by-pass —10— to the inlet port —3—.

The communication between the intake pipe —9— and port —7— is normally cut off by a self-closing valve —11— which, in this instance, is held to its seat by a spring —12— and is adapted to open against the action of said spring by the partial vacuum produced by the compression stroke of the main piston as —13— which is movable in the cylinder —1—.

The intake port —7— and exhaust port —4— are in such relative position that the piston —13— operates to open the port —4— full open and to entirely close the port —7— when at the limit of its outward stroke and to completely uncover the port —7— and close the port —4— when at the limit of its compression stroke so that as soon as the port —7— is uncovered during such compression stroke of the piston, the suction or partial vacuum produced thereby will operate to open the valve —11— against the action of the spring —12— thereby admitting the combustible fluid to the interior of the cylinder but at the outer end of the piston.

As soon as the piston —13— reaches the limit of its compression stroke at which time the previously introduced fresh charge of explosive mixture is compressed and ignited, the piston —13— is driven outwardly by the expansive force of the explosive mixture thereby forcing the fresh mixture below the

2

piston outwardly through the port —8— and by-pass —10— and thence through the inlet port —3— into the explosion chamber of the cylinder as soon as the latter port is uncovered during the out-stroke of said piston. This port —8— is spaced apart from the inlet port —3— a sufficient distance to remain open during all positions of the piston so that during the compression stroke the explosive mixture which is taken in through the port —7— readily passes into the base of the cylinder through the port —8— and into the by-pass —10— where it is highly compressed by the out-stroke of the piston and passes instantly under such pressure into the explosion chamber of the cylinder as soon as the port —3— is uncovered or opened. This opening of the port —3— takes place after the beginning of the opening of the exhaust port —4— which latter is full open by the time the inlet —3— is also full open so that the in-rushing fresh explosive mixture aids in expelling the spent gases from the exhaust port which expelling action is aided by the use of a baffle or deflector plate —14— on the compression end of the piston and in close proximity to the inlet port —3— by reason of the fact that said plate deflects the fresh inflowing explosive mixture upwardly, thereby displacing the spent gases from the opposite side.

Means for maintaining a maximum power under increased speed.—The maximum power of the engine under increased speed may be maintained by any suitable mechanism whereby the intake or exhaust port and preferably both of such ports may be gradually elongated as the speed of the engine increases and in order that this principle of my invention may be clearly understood I have shown a slideable sleeve —15— fitting closely within and adjustable lengthwise of the cylinder and having an internal bore in which the piston —13— is movable. This sleeve forms a part of the combustion chamber of the cylinder as well as a removable wearing sleeve for the piston and is provided with a series of ports —3'—, —4'—, —7'— and —8'— registering respectively with and shiftable relatively to the ports, —3—, —4—, —7— and —8— for the purpose of varying the size of the last named ports as may be required to maintain the maximum power of the engine under increased or maximum speed or in other words to compensate for decrease of power under increased speed.

It may be that under some conditions approximately the same result may be accomplished by varying the size of either the inlet or exhaust port separately and I, therefore, desire to claim means for varying the size of one of the ports for the purpose of compensating for the loss of power under

increased speed and although I have shown a sleeve slideable in the cylinder having ports registering with those in the cylinder it is evident that the same result may be accomplished by any rotary or longitudinal 70 slideable element having a port or ports movable relatively to those in the cylinder whereby the size of the inlet and exhaust ports may be varied at will or automatically if necessary to compensate for the loss of 75 power under increased speed.

Air pump.—A guide tube 16 which in this particular instance is formed integrally with, and extends some distance into the base of the main cylinder —1— receives an auxiliary guide piston —17—, the latter being connected by a rod —18— to the head of the piston —13— through a suitable guide or gland —19— in the inner end of the pump cylinder —16— whereby the piston —17— is caused to move with and through the same stroke as the piston —13—. The inner end of the pump cylinder aside from the gland —19— is closed and forms a compression chamber between 85 it and the head of the piston —17— into which atmospheric air is admitted through a passage —20— in the base of the tube —16—. This passage or inlet port —20— is located and uncovered at the limit of the 90 out-stroke of the head of the piston —17— but during the greater portion of such out-stroke a partial vacuum is created in the tube —16— between its inner end and piston so that as soon as the port —20— is uncovered 100 the atmospheric air rushes into the partial vacuum with considerable force thereby filling the tube with air at atmospheric pressure. During the compression stroke of both pistons this air in the tube —16— is 105 highly compressed and when the piston —17— approaches the limit of its compression stroke this compressed air is instantly forced into the interior of the main piston —13— through one or more passages —21— 110 in the sides of the rod —18—, it being understood that these passages —21— are of sufficient length to connect the interior of the tube —16— with the interior of the main cylinder —1— beneath the piston 115 —18— through the gland —19— when the piston —17— reaches the upper limit of its compression stroke.

The interior diameter of the piston —13— is greater than the exterior diameter of the 120 tube to receive the inner end of the tube —16— during the out-stroke of the main piston —13—, the intervening space between the tube —16— and piston —13— forming a passage for the escape of the atmospheric air which is compressed and discharged through the passages —21— at the limit of the compression stroke. This additional atmospheric air which is admitted through the inlet port —20— is, therefore, compressed into 125 130

the space between the inner end of the tube —16— and head of the piston —13— when the latter reaches the limit of its compression stroke so that immediately upon the return of the piston under expansive force of the explosive mixture the compressed air between the inner end of the tube —16— and head of the piston —13— is further compressed and forced outwardly through the ports —8'— and —8— and into the by-pass —10— and as soon as the ports —3— and —3'— are uncovered by the outward movement of the piston —13— this compressed air together with the explosive mixture which is drawn in through the intake —9— rushes into the combustion chamber through the ports —3— and —3'—, the additional compressed air serving not only to increase the explosive qualities and expansive force of the explosive mixture but also aids in cooling and cleansing the combustion chamber.

It is evident from the foregoing description that by providing means for increasing the size of the ports as the speed of the engine increases to compensate for loss of power under such increased speed the engine may be run at a much higher rate of speed than has heretofore been practical and that by introducing air in the manner described I am enabled thereby to keep the temperature of the cylinder down to a safe degree and that by twice compressing the additional atmospheric air which is thus introduced, once by the compression stroke of the piston —17— and again by the outward stroke of the piston —13—, I am enabled to introduce this air into the combustion chamber at a high degree of pressure which aids in cleaning the cylinder from spent gases during the reduced intervals of time between the opening and closing of the inlet and exhaust ports as the speed of the engine increases.

The sleeve —15— may be adjusted lengthwise of the cylinder by any suitable means and for this purpose I have shown a shaft —24— as journaled in suitable bearings upon and at one side of the base of the cylinder —16—, said shaft being provided with crank arms —25— which are connected by links or rods —26— to the outer end of the sleeve —15— said rods being guided in suitable bearings —27— which serve to hold the sleeve against turning and at the same time enable the sleeve to be adjusted endwise to shift the ports therein relatively to their corresponding ports in the cylinder.

The piston —17— is preferably hollow and is connected by a rod —28— in any well known manner to a suitable crank shaft not shown for the reason that the connection between the piston and crank shaft forms no part of my present invention.

In operation, assuming that the operating parts are in the position shown in Figs. 1

and 2 with the ports —3'—, —4'—, —7'— and —8'— of the sleeve —15— as partially open for low or normal speed, the pistons being at their extreme limit of outward stroke with the ports —3—, —4— and —20— open, then in this position the combustion chamber is filled with a fresh charge of the explosive mixture. Now during the compression stroke of the piston —13— the ports —3— and —4— are first closed whereupon the explosive mixture in the combustion chamber is compressed during which compression stroke the port —20— is closed and the air in the tube is compressed by the piston —17— and at the same time the gas fuel is compressed by the compression stroke of the piston —13— when the port —7— is uncovered causing the opening of the valve —11— to admit the explosive mixture from the intake to the cylinder beneath the piston —13— at which time the passages —21— are brought to a position to connect the interior of the tube with the interior of the main cylinder —1— beneath the piston allowing the compressed air to pass through the port —8— and into the by-pass —10—. Now as soon as the piston —13— reaches the limit of its compression stroke, the explosive mixture is ignited by any well known igniting means, not necessary to herein illustrate or describe, whereupon the exploded mixture returns the piston —13—, thereby closing the port —7— and opening the ports —3—, —4— and —20— which allows the previously compressed explosive mixture in the conduit —10— to pass immediately into the combustion chamber through the port —3— ready for a repetition of the operation just described, it being understood that the inflowing fresh mixture causes displacement of the spent gases through the exhaust port —4—.

What I claim is:

1. An internal combustion engine comprising a cylinder having an inlet port and an exhaust port, a piston controlling said ports, additional means movable between the piston and cylinder and movable relatively to the piston for additionally controlling said ports and an adjusting device for said means operable at will independently of the piston.

2. An internal combustion engine comprising a cylinder having an inlet and an exhaust port, a piston controlling said ports, and a sleeve between the piston and cylinder adjustable lengthwise for simultaneously varying the lead of said ports.

3. An internal combustion engine comprising a cylinder having an inlet port and an exhaust port, an axially adjustable sleeve within the cylinder for varying the lead of said ports, and a piston movable in the sleeve and controlling said ports.

4. An internal combustion engine comprising a cylinder having an inlet port and an exhaust port, a piston controlling said ports, and means within the cylinder movable relatively to and independently of the piston for simultaneously varying the size of said ports. 45
5. An internal combustion engine comprising a cylinder having an inlet port and an exhaust port, a sleeve slidable endwise of and within the cylinder across said ports, a piston movable in the sleeve and controlling said ports and means for adjusting said sleeve at will. 50
- 10 6. An internal combustion engine comprising a cylinder having an inlet port and an exhaust port, a piston controlling said ports, and a sleeve surrounding the piston and adjustable endwise relatively to the piston and cylinder across said ports and means operable at will for moving said sleeve endwise. 60
- 15 7. In a combustion engine, a cylinder having an inlet and an exhaust port, a movable member within the cylinder having ports registering with and movable relatively to the first named ports, a piston controlling said ports and means to actuate said member at will independently of the piston. 65
- 20 8. A combustion engine comprising a cylinder having an inlet port and an exhaust port, a sleeve movable in the cylinder and provided with ports registering with and adjustable relatively to the first named ports, and a piston movable in the sleeve and controlling said ports. 70
- 25 9. A combustion engine comprising a cylinder having an inlet port and an exhaust port, a sleeve slidable lengthwise of the cylinder and provided with ports registering with and adjustable relatively to the first named ports, and a piston movable in the cylinder and controlling said ports. 75
